UNITED STATES PATENT OFFICE.

GUSTAVE F. SCHMIDT, OF CHICAGO, ILLINOIS.

GENERATOR.

Application filed January 15, 1926. Serial No. 81,357.

My invention relates to a generator intended for vaporizing and gasifying hydrocarbon fuel and more especially kerosene; the object of the invention being to provide a generator 5 wherein rapid vaporization and gasification will occur and be maintained during operation of the generator.

Another object of my invention is to provide a generator wherein the fuel is made to 10 travel intermediate of and in contact with comparatively rapidly heating and at the same time heat retaining elements; the fuel passage being such that merely a minute quantity of fuel, substantially in the form of a 15 thin film is enabled to travel through the generator which comprises an outer metal tube and an inner tube of a hard non-porous carbon consisting of a specifically treated petroleum coke base impervious to the liquid fuel and 20 which at the same time acts as a catalytic agent during passage of the hydrocarbon fuel through the generator.

With my improved generator, the gasification of the liquid fuel is effected in a passage alternately consisting of walls of metal and the hard non-porous carbon and tendency toward carbonization is thus entirely eliminated.

Another object of my invention is to provide 25 a generator wherein all vaporized and gasified fuel will be discharged when the supply of liquid fuel or kerosene to the generator is shut off, so that condensation in the generator proper cannot take place and as a result no 30 carbon deposit is formed.

The objects and advantages of my invention will be fully comprehended from the detailed description of the accompanying drawing, wherein:—

40 Figure 1 is a perspective view of my improved generator shown applied to a radiant heater type of burner.

Figure 2 is a longitudinal sectional view of the generator and mixing chamber with a portion 45 of the burner shown in Figure 1.

Figure 3 is a cross sectional view of the generator at any point intermediate of the ends.

For the purposes of exemplification, I have 50 shown my improved generator shown at 15 connected to a burner 16 provided with burner-tips 17 having suitable grids 18; one end of the burner being shown with a portion of a radiant rest 19 and portions of a pair 55 of radiants 20.

The chamber of the burner is preferably

formed with a bottom sloping from both ends towards an intermediate point as shown at 21 in Figure 1 to permit drain of any condensate that may accumulate; a suitable pet or drain 60 cock being shown at 22.

The side of the burner 16 is shown provided with a mixing chamber 23, comprising a conduit open at bottom to atmosphere, while the upper end is closed and adjacent to the end at 65 a point in axial alignment with the discharge of the generator 15 is provided with a short tube 24 which communicates with the connection 25 leading to the chamber of the burner; the end of tube 24 being disposed at a predetermined distance relative to the discharge opening of the generator. The side wall of the mixing chamber is shown provided with a connection or nipple 26 having a reduced 70 passage 27 therethrough; the initial end of the passage being properly formed to receive the tapered end 28 of a valve-stem 29; while the discharge end of the nipple 26 is shown preferably provided with a removable member or 75 small tip 30, the end wall 31 whereof is provided with a small needle port. The inner end of tip 30 may extend into abutting relation with the shoulder 32 of the nipple 26; the port in the end 31 of the tip 30 is adapted to receive the clean-out needle 33.

With the arrangement just described, it is apparent that the discharge end of the generator may be readily cleaned and the tip may be renewed should occasion require.

The initial or large end of the nipple 26 is 80 formed to receive the end of the main tube 34 of the generator 15; the tube 34 like the nipple 26 being of suitable heat conducting metal.

The opening in the mixing chamber 23 is 85 formed so that the nipple 26 and the generator will be disposed parallel with and in close proximity to the side of the burner 16 which is provided with a suitable number of the jets 35, positioned to play on the outer tube 34 of the generator.

The initial end of the generator tube 34 is 90 provided with a member 36 internally threaded at one end to receive the threaded portion of the valve-stem 29. The passage in the coupling 36 just beyond the inlet port 37 is 95 tapered at 38 to provide a seat for the enlarged beveled portion 39 of the valve-stem whereby flow of the liquid fuel into the main portion of the generator is controlled and entirely shut off when said portion 39 is on 100 its seat.

The port 37 receives the liquid fuel or kero-

sene by means of tube 40 (only a portion of which is shown) which connects with a suitably supply.

The outer end of the coupling 36 is externally threaded to receive gland nut 41 through which the valve-stem extends; the nut 41 compressing the packing element 42 into oil-tight relation with the stem.

The generator 15 also comprises a carbon tube 43 of a diameter but slightly smaller than the internal diameter of the outer metal tube 34, so as to provide a very minute or attenuated passage between the two tubes for passage of the hydrocarbon fuel; in other words merely a fine film of infinitesimal quantity of fuel can pass between the two tubes (see Fig. 3). The carbon tube 43 preferably extends throughout the length of outer tube 34; and the opening through the carbon tube 43 is such that a small or narrow passage intermediate of the valve-stem 29 and the inner wall of the carbon tube 43 for passage of the fluid fuel is provided; this passage, like that between the two tubes, being such that a film like quantity of fuel can flow therethrough.

The bore at the initial end of the nipple 26 is such that the resultant gaseous medium formed intermediate of the two tubes and intermediate of the inner carbon tube and the valve-stem will be compelled to flow past the tapered end 28 of the valve-stem 29, thence through the needle controlled port and into the mixing chamber; the gaseous stream being injected into the tube 24 and entraining air therewith, so that a combustible gaseous mixture is introduced by the short tube 24 into the burner body.

As is usual with generators and burners employing hydrocarbon fuel, the initial heating is accomplished by extraneous means, such as an alcohol flame; the metal of the generator and burner becoming properly heated soon causes a gasification of the hydrocarbon fuel within the generator tubes and ignition at the burner tips 17 and 35 may take place.

In the operation of my apparatus, the shut-off valve 39 is kept closed so that no kerosene or liquid fuel is permitted to enter the generator until the latter has been heated to a proper temperature, at which time the valve 39 is opened gradually; the nature of the valve permitting such regulation that the proper amount of kerosene enters the attenuated passages of the generator portion of the apparatus. The relation between the fuel admitting valve 39 and the vapor or gaseous medium control end of stem 29, namely the tapered end 28 and needle 38, is such that the tapered end 28 will merely control the amount of vapor discharged from the generator proper and seating of the end 28 made impossible, as the beveled valve portion 39 will completely seat and close off inflow of hydro-carbon fuel before the tapered end 28 reaches its seat. This relation between the

valves just described is of great importance in the successful operation of apparatus of the type here in question wherein hydrocarbon fuels, such as kerosene, are employed, as discharge of all the generated vapor should be permitted after valve 39 is closed, so as to prevent condensation in the generator passages.

With my arrangement, a dry generator is at all times maintained when flow thereto is discontinued and as a result formation of carbon in the generator is made impossible, as the admission of the liquid fuel is at the coolest point of the apparatus, namely in advance of the generating channels or portion; the temperature of the latter increasing toward the discharge end thereof. This is not the case with apparatus as at present employed, wherein the generator is frequently located at a suitable point above the burner portion with connections from the generator extending downward at the side of the burner and therefore beyond the heating zone; with the result that a chilling and condensation of the gaseous medium at least to a certain degree, takes place before it is discharged into the mixing chamber of the burner. With such constructions, improper combustion is obtained, carbon formation takes place, and unpleasant odors result. With my improved generator, these conditions are eliminated and a stream of practically invisible gas is discharged into the burner as soon as the apparatus is in proper condition and operation and a greatly superior heating flame is provided.

Porous substances and solid carbon sticks have been employed in generators of the type here in question for the purpose of filtering the liquid fuel or to act as heating agents. The use of a porous element permits formation of carbon, the very thing not desired and which is entirely prevented by my improved generator. Furthermore, the use of a solid carbon stick is not feasible because it prevents the use of clean-out points or needles at the discharge tip of the generator and controllable by the valve-stem and which is of great importance because the discharge tips of the generators are usually located at a more or less inaccessible point where it is impossible to insert a fine needle point from the outside. Due to a certain tendency of the vapor to carbonize at the minute discharge opening of the tip, it is essential to provide a clean-out point which may be actuated with each operation of the valve-stem to prevent clogging and insure proper operation.

I provide a hard carbon tube which not only permits passage of the valve-stem therethrough, but which at the same time will heat more quickly than would a solid stick, while also retaining heat a sufficient length of time. The tube 43 of my generator is formed of a

substance of somewhat amorphous nature having a petroleum coke base specially treated and baked to provide the non-porous carbon tube possessing catalytic properties when heated and in contact with the volatilized hydrocarbon, with the result that a gaseous medium is obtained superior to that heretofore possible with generators of the type as previously constructed.

10 In order to insure against possibility of the accumulation of matter intermediate of the metallic tube 34 and the carbon tube 43, means are provided whereby the carbon tube is given rotary movement during each operation of the valve-stem 29. I, therefore, show the end of the carbon tube 43 adjacent to the valve housing or coupling 36, with small slots 44 which receive the ends of a pin 45 disposed transversely through the valve-stem 29. It is apparent from this construction that the carbon tube will be rotated within metal tube 34, whenever the valve-stem is turned, coking of the accumulated matter and clogging of the small passage thus prevented.

With my improved method, the hydrocarbon fuel in controllable quantities enters the generator through the control valve 39 and is admitted into the coolest part of the generator where it fills the minute space or spaces between the two tubes and between the carbon tube or catalytic agent and the valve-stem. The hydrocarbon coming into contact with the moderately heated end of the catalytic agent is atomized and distributed in a very thin film and in its further travel lengthwise of the catalytic agent, and therefore over a surface of increasing temperature toward the discharge opening, vaporization and gasification take place before discharge from the generator, with the result that a pure and invisible gas is discharged into the mixing chamber.

With my improved apparatus, the generator is absolutely dry before any hydrocarbon is admitted; the minute passages in the generator being filled at the initial end will serve to counterbalance any back pressure of the gas created and thus prevents a pulsating action of the flame in the burner.

The exemplification disclosed is well adapted to carry out the method herein set forth; the apparatus having been described in terms employed merely as terms of description and not as terms of limitation, as modifications are possible and may be made without, however, departing from the spirit of my invention.

What I claim is:

1. A generator of the character described, comprising an outer metallic tube, a non-porous carbon tube, the external diameter whereof is slightly less than the inner diameter of the outer tube and resting at bottom on the metal tube so as to provide an attenu-

ated crescent shaped passage for the hydrocarbon between the outer tube and the upper surface of the carbon tube, and a metal rod passing through the carbon tube and of a diameter slightly less than the internal diameter of the carbon tube so as to provide an attenuated crescent shaped passage beneath the rod. 70

2. A generator of the character described, comprising a pair of tubes arranged one within the other, and a stem or rod disposed through the inner tube, the outer diameter of the inner tube approximating the inner diameter of the outer tube while the diameter of the stem or rod approximates the inner diameter of the inner tube, whereby a pair of attenuated long passages are provided and the hydrocarbon fuel caused to flow in the form of a film, a fuel admitting valve at the initial ends of said passages, and a vapor controlling valve at the discharge ends of the passages. 75

3. A generator of the character described, comprising a pair of tubes arranged one within the other so as to cause the liquid fuel to pass therebetween in the form of a film, the tubes being heated to an increasing temperature toward the delivery ends, a fuel admitting valve at the initial ends of the tubes, vapor flow controlling means at the outlet ends of the tubes, and common means whereby the fuel admitting valve and said vapor controlling means are actuated. 90

4. A generator of the character described, comprising a metallic tube, a tubular catalytic element of heat conducting material arranged within the metallic tube so as to provide an attenuated passage adapted to receive a film of liquid fuel therebetween, a fuel control valve at the initial end of the tube, a metallic stem disposed through said element, a vapor control valve at the inner end of said stem, and means whereby said tubular element is rotated when said vapor control valve is actuated. 100

5. A generator of the character described, comprising a member adapted for passage of the liquid fuel therethrough, a shut-off valve in said member, a mixing chamber open to the atmosphere and having an injecting nozzle in the side wall thereof, a removable tip at the delivery end of the nozzle having a minute port therethrough, a pair of tubes arranged one within the other and disposed intermediate of the first mentioned member and said nozzle, and a valve-stem disposed through the inner tube, provided with a clean-out needle for said port and formed at its inner end to control flow of vapor through said nipple and tip. 110

6. A generator of the character described comprising an outer metallic tube, a tubular catalytic element having an outer diameter approximating the inner diameter of the outer tube, a metallic rod disposed through the catalytic element and having an outer diameter approximating the inner diameter of said 125

element, said tube, element and rod being so arranged that thin passages intermediate of the outer tube and catalytic element and intermediate of the catalytic element and the rod are provided extending from end to end and of crescent shape, and a valve at the initial end of said tube whereby flow into said passages is controlled.

7. A generator of the character described comprising an outer tube, a catalytic element arranged lengthwise within said tube so as to provide an attenuated passage intermediate of one side of said element and the inner wall of said tube, said element being provided with an attenuated passage therethrough, a common discharge member at the delivery ends of said passages, and common means for controlling inflow of hydrocarbon fuel at the opposite ends of said passages.

8. A generator of the character described comprising a metallic tube, a catalytic element arranged lengthwise within said tube so as to provide a thin passage therebetween extending from end to end, said element also having

a passage therethrough, a common discharge member for both passages arranged concentric and in alignment with said tube and element, a fuel control valve at the initial ends of said passages, and means whereby said element may be given movement relative to said tube.

9. A generator of the character described, comprising an outer tube, a non-porous carbon tube having an outer diameter approximating the inner diameter of the outer tube and extending from end to end within said outer tube whereby an attenuated passage between said tubes is provided, a rod whose diameter approximates the inner diameter of said carbon tube, extending from end to end within said carbon tube whereby an attenuated passage through the carbon tube is provided, controllable fluid admitting means common to both of said passages, and a common discharge nipple concentric with the delivery ends of said tubes.

GUSTAVE F. SCHMIDT.
